FOREIGN PATENT DOCUMENTS

KR 300922022.0000 * 9/2017

Primary Examiner — Karen E Eldridge Powers(74) *Attorney, Agent, or Firm* — Bond Schoenbeck & King, PLLC; George McGuire(57) **CLAIM**

The ornamental design for a floor mat brushing cap, as shown and described.

DESCRIPTION

FIG. 1 is a perspective view of a floor mat brushing cap; FIG. 2 is a front elevation view thereof; FIG. 3 is a rear elevation view thereof; FIG. 4 is a first side elevation view thereof; FIG. 5 is a second and opposite side elevation view thereof; FIG. 6 is a top plan view thereof; and, FIG. 7 is a bottom plan view thereof.

Features of the floor mat brushing cap shown in broken lines in the drawings illustrate environmental structure and form no part of the claimed design.
